[57] CLAIM

The ornamental design for an entertainment storage unit, as shown and described.

DESCRIPTION

FIG. 1 is a top view of an entertainment storage unit showing my new design;

FIG. 2 is a perspective view thereof;

FIG. 3 is a front view thereof; and,

FIG. 4 is a left side elevational view as seen when in use, the right side being a mirror image thereof.

The rear of the unit not shown forms no part of the claimed design.
